US00D963340S

(12) **United States Design Patent** (10) **Patent No.:** **US D963,340 S**
(45) **Date of Patent:** **** Sep. 13, 2022**

(54) **CASE**

(71) Applicant: **Dengfeng Zhu**, Zhangjiajie (CN)

(72) Inventor: **Dengfeng Zhu**, Zhangjiajie (CN)

(**) Term: **15 Years**

(21) Appl. No.: **29/782,745**

(22) Filed: **May 8, 2021**

(51) **LOC (13) Cl.** **03-01**

(52) **U.S. Cl.**

USPC **D3/301**

(58) **Field of Classification Search**

USPC D3/276, 282, 289, 295, 301, 302, 294

CPC Y10S 190/903; A45C 2011/003

See application file for complete search history.
